No. 37,381.

Patented February 7, 1905.

UNITED STATES PATENT OFFICE.

ADA LOUISE GREENWOOD, OF NEW YORK, N. Y., ASSIGNOR TO THE STEWART, HOWE & MAY COMPANY, A CORPORATION OF NEW JERSEY.

DESIGN FOR A BELT.

SPECIFICATION forming part of Design No. 37,381, dated February 7, 1905.

Application filed December 19, 1904. Serial No. 237,583. Term of patent 3½ years.

To all whom it may concern:

Be it known that I, ADA LOUISE GREENWOOD, a citizen of the United States, residing in the city, county, and State of New York, have 5 invented a new, original, and ornamental Design for a Belt, reference being had to the accompanying drawing, forming part thereof, the same being a perspective view of said design.

What I claim as new, and desire to secure to by Letters Patent, is—

The ornamental design for a belt, substantially as shown.

ADA LOUISE GREENWOOD.
